CONTROL PANEL FOR AN ELECTRIC ORGAN

John M. Hanert, Des Plaines, Ill., assignor to Hammond Organ Company, Chicago, Ill., a corporation of Delaware

Filed Sept. 25, 1959, Ser. No. 57,685

Term of patent 14 years

(Cl. D56—2)

Fig. 1 is a front elevational view of a control panel for an electric organ showing my design; and

Fig. 2 is a sectional view of the panel taken on the line 2—2 of Fig. 1 in the direction indicated by the arrows.

The broken line showing of a music rack and a portion of an organ console is for illustrative purpose only.

I claim:

The ornamental design for a control panel for an electric organ, as shown and described.
